US00D656147S

(12) **United States Design Patent**
Schlossstein

(10) **Patent No.:** **US D656,147 S**
(45) **Date of Patent:** **** Mar. 20, 2012**

(54) **USB MEMORY DEVICE**

(76) Inventor: **Karl Phillip Schlossstein**, London (GB)

(**) Term: **14 Years**

(21) Appl. No.: **29/383,291**

(22) Filed: **Jan. 14, 2011**

(30) **Foreign Application Priority Data**

Aug. 2, 2010 (EM) 001739061-0001

(51) **LOC (9) Cl.** **14-02**

(52) **U.S. Cl.** **D14/480.6; D14/436**

(58) **Field of Classification Search** D14/411,
D14/433, 435.1, 436, 480.1–480.7, 484.1,

(57) **CLAIM**

The ornamental design for a USB memory device, as shown and described.

DESCRIPTION

FIG. 1 is a top front right perspective view of the USB memory device.

FIG. 2 is a right side elevational view of the USB memory device.

FIG. 3 is a front elevational view of the USB memory device.

FIG. 4 is a top plan view of the USB memory device.

FIG. 5 is a bottom rear right perspective view of the USB memory device.

FIG. 6 is a top front left perspective view of the USB memory device where the USB connector has been positioned to extend out the front; and,

FIG. 7 is a bottom rear right perspective view of the USB memory device where the USB connector has been positioned to extend out the front.
